United States Patent Office

Des. 221,855

Patented Sept. 14, 1971

221,855

BLADE FOR A DENTAL INSTRUMENT

James Vannes Boone, Meadows Bldg.,
Dallas, Tex. 75206

Filed Oct. 13, 1969, Ser. No. 19,514

Term of patent 14 years

Int. Cl. D24—03

U.S. Cl. D24—1

FIG. 1

FIG. 2

FIG. 3

FIG. 1 is a top plan view of a blade for a dental instrument showing my new design.

FIG. 2 is a bottom view of the blade shown in FIG. 1; and

FIG. 3 is a side view of the blade of FIGS. 1 and 2, and showing the blade in a flat position.

I claim:

The ornamental design of a blade for a dental instrument, as shown.
